UNITED STATES PATENT OFFICE.

GENNARO DE BELLIS, OF PHILADELPHIA, PENNSYLVANIA.

DESIGN FOR A SPEAKING-TRUMPET.

52,909.

Specification for Design.

Patented Jan. 28, 1919.

Application filed November 30, 1918. Serial No. 264,864. Term of patent 14 years.

To all whom it may concern:

Be it known that I, GENNARO DE BELLIS, a citizen of the United States, residing at Philadelphia, in the county of Philadelphia and State of Pennsylvania, have invented a new, original, and ornamental Design for Speaking-Trumpets, of which the following is a specification, reference being had to the accompanying drawing, forming a part thereof, in which—

Figure 1 is a perspective view,
Fig. 2 is a side elevation, and
Fig. 3 is an end view.

I claim:

The ornamental design for a speaking trumpet, as shown.

GENNARO DE BELLIS.

Witnesses:

MARY A. INGLAS,
CHAS E. POTTS.
